UNITED STATES PATENT OFFICE.

ST CHARLES JACOBS, OF BROOKLYN, NEW YORK.

WASHING MACHINE.

Application filed July 26, 1920. Serial No. 398,924.

To all whom it may concern:

Be it known that I, ST CHARLES JACOBS, a citizen of the United States, and a resident of Coney Island, borough of Brooklyn, in the county of Kings and State of New York, have invented certain new and useful Improvements in a Washing Machine, of which the following is a full, clear, and exact specification.

10 This invention relates more particularly to a class of apparatus adapted to be used for laundering purposes.

My invention has for its object primarily to provide a machine designed to be employed for washing clothes and other articles of washable character in a manner so that the work will be accomplished effectually and with facility without requiring laborious hand scrubbing on a wash board and the like as is incident to ordinary methods. The invention consists essentially of a tank for holding liquid, and in the tank is a container or casing with an entrance for reception of washable articles. The container is smaller than the tank, and the container is held in suspension in the tank by mechanism which is manually operable for swinging the container back and forth. In opposite parts of the container are two openings so that when the container is swung the liquid of the tank will be admitted into the container and discharged therefrom through the openings alternately for causing the liquid to flow in opposite directions through the container whereby the contents of the container will be washed by being subjected to currents of the liquid.

Another object of the invention is to provide across each opening a distributor for dividing into small streams the currents of the liquid at their admission into the container; and a further object of the invention is to provide a washing machine of a simple efficient and durable construction which may be made in any suitable size and shape.

With these and other objects in view, the invention will be hereinafter more particularly described with reference to the accompanying drawing forming a part of this specification in which similar characters of reference indicate corresponding parts in all the views, and will then be pointed out in the claims at the end of the description.

In the drawing, Figure 1 is a fragmentary view showing a detail longitudinal vertical section taken through the tank as well as

showing an elevation of the container and mechanism by which it is swung of one form of washing machine embodying my invention, and

Fig. 2 is a detail sectional view taken on the line 2—2 of Fig. 1.

The machine has a tank 10 which may be of any suitable size and shape for holding water or other liquid for washing clothes and other articles, though the form of the tank illustrated is substantially rectangular, as viewed lengthwise, to provide side walls 11, 12 and end walls 13, 14, while the bottom 15 of the tank may be curved. The top of the tank may be open, as at 16, to allow washing liquid to be admitted therein, and the tank may be drained when desired through a valve or cock, as 17, of any well known or preferred form which is preferably provided centrally of one end of the bottom of the tank. The tank may be supported on a number of legs, as 18, and the open top of the tank may be closed if desired by a suitable removable cover, not shown.

Interiorly of the tank 10 is a container or casing 19 which is considerably smaller than the tank, and this container may be of any appropriate shape, though the container has a cylindrical body part 20 with an entrance 21 in the top of its central part to allow clothes, linens and other washable articles to be removably placed within and removed from the container. The entrance 21 is adapted to be opened and closed by a cover 22 which is hinged, at 23, to the body part of the container. The body part 20 of the container 19 is tubular to provide open ends or openings 24 and 25 in opposite parts thereof. On the body part 20 at the opening 24 of the container may be an outwardly flaring annular flange 26, and on the body part at the opening 25 may be another outwardly flaring annular flange 27. The flanges 26 and 27 are, therefore, somewhat funnel shaped, and by providing the openings 24 and 25 with these flanges, washing liquid in the tank 10 will be admitted into the container and discharged therefrom in currents first through one opening and its flange and then through the other opening and its flange when the container is swung back and forth in the tank, as will be hereinafter more fully explained.

Across the opening 24 of the body part of the container is a stationary distributor 28, and across the opening 25 of the body part

2
is a second fixed distributer 29. These distributers are preferably similarly formed, and each distributor may consist of a perforated plate or sheet of interwoven wire cloth to provide interstices, as 30, so that the currents of liquid from the tank which is admitted into the funnel shaped flanges 26 and 27 will be distributed into fine streams during their flow into the body part of the container through the openings 24 and 25 when the container is oscillated.

In order to cause the container 19 to be swung back and forth in rapid succession for effectually employing the liquid to wash articles in the container, I provide a mechanism, as 31, which also supports the containers in suspension for being oscillated in the tank. Any suitable form of mechanism may be used, but the form shown is composed of a yoke or inverted U-shaped prongs or strap 32 which is disposed in straddle arrangement over the central part of the body 20. The ends of the prongs 32 are rotatably held to lugs or pins 33 and 34 which protrude laterally in opposite directions from the central part of the exterior of the cylindrical body 20 of the container 19 so that the container is balanced between the prongs for being easily swung back and forth in the tank in the radius of a circle. The curvature of the U-shaped prongs are considerably larger than the body part 20 of the container to permit free movement of the container, and from the center of the U-shaped prongs is an upwardly extending bar 35 which terminates with a sleeve 36 some distance above the open top of the tank. At the upper edges of the side walls of the tank are held the lower ends of two brackets 37 and 38 which extend above the tank, and journaled in the upper ends of these brackets is a bar or shaft 39 disposed across the open top of the tank. The sleeve 36 of the pronged bar 35 is held to the shaft 39, and to one end of the shaft 39 is held the upper end of a crank arm 40 which depends downwardly exteriorly of the tank. To the lower end of the crank arm 40 is pivoted, at 41, one end of a bar 42 disposed right angularly to the crank arm. The second end of the bar 42 is pivoted, at 43, to the central part of a lever 44 which is vertically arranged so that its upper end extends above as well as extending alongside the tank to serve as a handle whereby the lever may be manually moved, and the lower end of the lever is pivoted, at 45, to the tank.

To operate the machine following the placing of washable articles in the body part 20 of the container 19, and following the pouring of sufficient water with other desired washing materials in the tank 10, the lever 44 is manually swung back and forth on its pivot. With the movements of the lever the bar 42 and crank arm 40 will like-

wise be swung back and forth. The shaft 39 will then be partially rotated for swinging the bar 35, the prongs 32, and the container 19 will thereby be oscillated in the tank in the radius of a circle. With the 70 swinging of the container in one direction the liquid of the tank will be admitted thereinto through one of its funnel shaped flanges and through the adjacent distributer. When the container is swung in the opposite direction the water in the container will be discharged through this distributer and currents of water will be admitted through the other funnel shaped flange and its associate distributer. Thus the contents of the container will be subjected to alternate currents of the liquid, and by providing the intersticed distributers 28 and 29 in the manner described the currents of liquid will be distributed into small streams and cause the 85 articles being washed to be thoroughly suded or saponified when the washing liquid is charged with soap.

In the foregoing description, I have embodied the preferred form of my invention, 90 but I do not wish to be understood as limiting myself thereto, as I am aware that modifications may be made therein without departing from the principle or sacrificing any of the advantages of this invention, 95 therefore I reserve to myself the right to make such changes as fairly fall within the scope thereof.

Having thus described my invention, I claim as new and desire to secure by Letters 100 Patent:—

1. The combination, in a washing machine, with a tank for holding liquid, of a tubular container with an entrance within the tank, mechanism supporting the container in suspension in the tank and the mechanism being operable for swinging the container back and forth, outwardly flaring flanges surrounding the open ends of the container so that when the container is swung the liquid 110 in the tank will be admitted into the container and discharged therefrom through the flanges and openings alternately so that the liquid will flow in opposite directions through the container, and intersticed elements across the open ends of the tubular container.

2. The combination, in a washing machine, with a tank for holding liquid, of a container having a tubular body with a door 120 closed entrance within the tank, an oscillatory yoke supporting the container in suspension in the tank, lever operable mechanism for causing said yoke with the container to be swung back and forth so that 125 the liquid in the tank will be admitted into the container and discharged therefrom through the open ends of its body alternately for causing the liquid to flow in opposite directions through the container, and 130

intersticed elements across the open ends of the tubular body.

3. The combination, in a washing machine, with a tank for holding liquid, of a container having a tubular body with a door closed entrance within the tank, an oscillatory yoke supporting the container in suspension in the tank, lever operable mechanism for causing said yoke with the container to be swung back and forth so that the liquid in the tank will be admitted into the container and discharged therefrom

through the open ends of the body alternately for causing the liquid to flow in opposite directions in currents through the container, and intersticed elements across the open ends of the body of the container.

This specification signed and witnessed this 24 day of July, A. D. 1920.

ST CHARLES JACOBS.
